UNITED STATES PATENT OFFICE.

EARL S. GIBSON, OF RIDGEWOOD, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed July 16, 1924. Serial No. 726,241.

This invention relates to telephone exchange systems, and more particularly to systems employing automatic switching apparatus for establishing connections.

For systems involving equipment for the completion of toll and long distance connections, it is desirable to permit the completing operator to set up a connection to a called line although such line may be busy at the time. By thus interposing, the operator may apprise the called party that a toll call is waiting his attention, giving him the option of continuing his present conversation or of discontinuing the same and receiving the toll call. If he decides to disregard the call, the operator must then release the switches which have built up the connection to his line. Inasmuch as the sleeve conductor of the operator's connection has been extended to the sleeve conductor of the called line, which is busy, this busy condition would ordinarily be transmitted to the sleeve conductor of said connection, thereby preventing the operator from releasing the switches she had set.

Accordingly, it is the object of this invention to enable the release of connections which have been set up to busy lines.

A feature of the invention relates to means for extending a connection over a trunk to a line, the release of the trunk being normally under the control of said line, together with means for rendering the release control of such trunk independent of the line to enable the release of the trunk after a conversational connection has been extended to the line when it is busy.

Another feature relates to an arrangement including a coordinate connector switch having a special link circuit whereby the release of a connection over an incoming trunk to a called line may either be placed under the control of the called line or may be effected immediately by an operator independent of the continued busy condition of said line.

Other advantages of this invention will appear more specifically from the following detailed description and also from the appended claims.

Referring to the drawing, Figs. 1 to 5, inclusive, when taken in the order illustrated in Fig. 6, disclose a sufficient amount of a telephone exchange system employing the

features of this invention to enable an understanding thereof. 55

Fig. 1 at the top illustrates schematically a local connection extended through a line switch and a district selector switch. At the bottom of this figure there is illustrated an incoming trunk from a distant office, together with an operator's position and her position equipment. The figure also shows schematically a sender selector switch and one of a number of register senders. 65

Fig. 2 illustrates a portion of two different incoming selector switches. 70

Fig. 3 illustrates a portion of a final or connector switch having access to called subscribers' lines. 75

Fig. 4 shows a part of one of a number of switch controlling markers and also a connecting device for associating these markers with the senders. 80

Fig. 5 illustrates schematically frame and trunk connectors for associating the markers with the incoming and final switches. 85

The system disclosed herein is arranged to handle both local calls and calls incoming from distant offices. The local lines 100 terminate in line switches 101 which have access to trunks as 102 leading to district selector switches as 103. The district selector switches 103 have access to trunks such as 115, which terminate in vertical rows of contacts 213 and 214 on incoming selector switches as 200. The incoming selector switches 200, only one of which is shown herein, have access to groups of trunks extending to final connector switches 300. For instance, one group of trunks may appear in the vertical row of contacts 215, while another group of trunks appear in the vertical row of contacts 216, etc. 90

The connector switches 300 are divided 95 into a number of groups, each group having access to a different portion of the total subscribers' lines. The group of trunks appearing in the vertical row 215 comprising the trunks 217, 218 etc., extend and appear in connector switches of a particular group. The group of trunks appearing in the vertical row 216 of the incoming switch 200 comprising the trunks 219 and 220, extend and appear in a different group 100 of connector switches one of which, switch 300, is shown. For instance, the trunk 220 which is shown in full herein appears in 105

the vertical row of contacts 301 in the connector switch 300 having access to a horizontal link in each of the units sections 310, 311 of the switch. Likewise, other groups of trunks outgoing from the incoming switches 200 appear in still other groups of connector switches. Each of the trunks of the several groups are multiplied to appear in all of the incoming switches comprising a particular group.

In addition to the equipment provided for local calls, the office is also provided with operator's positions as shown in Fig. 1. The trunks, such as trunk 106, incoming 15 from distant offices may serve to extend toll or long distance connections or for other similar purposes, and these trunks appear in the vertical rows of contacts of a special group of incoming selector switches one of 20 which, switch 201, is illustrated. The particular trunk 106, which is only shown partially, will be seen to appear in the vertical row of contacts 202 of the switch 201. Another trunk of similar nature and also under the control of the operator appears in 25 row 203. At each operator's position there are provided a keyboard 105, an assignment key 112 and a release key 113 individual to each of the trunks over which such operator has control.

The special incoming selector switches 201 have access to groups of operators' trunks extending to the several different groups of connector switches. For example, the vertical row of contacts 205 may include several of these operators' trunks, all of which lead to connector switches 300 of the same connector group. It will be noted that the trunk 220 appearing in the row 205 is also 30 the same trunk which is multiplied to appear in the row 216 of the regular incoming selector switches 200. This trunk will be the last trunk in the group with respect to the incoming selector switches 200. The next 35 operator's trunk 222 appearing in the row 205 of switch 201 will be the last trunk in another group of trunks outgoing from the incoming switches 200 appearing in the same group of connector switches 300. Similarly, 40 the same is true with respect to trunks 223 and 227. Thus, trunks 220, 222, 223 and 227 are each respectively the last trunk in four different groups of trunks outgoing from the incoming selector switches 200 to the same 45 group of connector switches including switch 300; and these four different operators' trunks are all combined in the same vertical row of contacts 205 in the special incoming switches 201. In a similar manner, the four 50 operators' trunks appearing in the vertical row 204 of switches 201 are the last trunks in four corresponding groups outgoing from the incoming switches 200 and appearing in a second group of connector switches 300. 55 The same may be true for as many groups

of connector switches 300 as there are provided.

Thus it will be seen that these special operators' trunks 220, etc., serve both for local mechanical connections and are also 70 employed for interoffice connections where an operator is involved.

The operators' trunks of a particular group are arranged to appear before a corresponding horizontal link on each of the 75 several connector switches 300 of the connector group. Each trunk, however, appears in a different vertical row of contacts of the connector switches 300. For example, the trunk 220 appears before the 80 horizontal links 313, 314, etc., in the vertical row 301 of the connector switch 300 and similarly before corresponding links in other connector switches. The second trunk 222 appears before the links 313, 314, etc., in 85 the vertical row 302 of the connector 300. The same is true with respect to the other trunks of the operator's trunk group.

Both the local trunks 102 and the incoming trunks 106 may be associated with 90 idle register senders by means of sender selector switches. In practice there may be two types of senders 107 one to be used for local connections and the other to be used for incoming calls. Accordingly the local 95 trunks 102 may be associated with one kind of sender through one sender selector switch 104 whereas the incoming trunks 106 may be associated with the other kind of sender through another sender selector 104. For 100 convenience in the drawing, however, both local and incoming trunks have been shown as appearing in the single sender selector frame 104 and no attempt has been made to disclose the details of the different types 105 of senders.

Each of the several register senders, such as the sender 107, may be associated with any one of a number of markers, part of one of such markers being shown in Fig. 4. For 110 this purpose a sender connector device 400 made up of a number of multi-contact relays is provided for connecting any one of the senders to the first idle marker. The marker receives the record registered in the sender 115 and thereupon determines the selective operation of the incoming and final switches to complete the connection to the wanted line.

After the record has been received in the 120 marker, such marker is associated with an incoming switch frame by means of a frame connector 500. The group of testing relays 401 in the marker are thereby connected to the test conductors of the horizontal links 125 of the incoming switch. In case the connection being extended is one involving a local line and thereby involving the incoming switch 200, the marker is further associated with the trunks outgoing from the 130

incoming switch to the connector switch by means of a trunk connector 501.

Moreover, the marker is associated through a connecting device 502 with the proper connector switch 300 in the particular group, having access to the called subscriber's line. By reason of this association, the testing relays 401 are connected to the horizontal links of the proper units sections 310 or 10 311, etc., in the connector switch. Thus a test is made to determine an idle link in the incoming switch corresponding to an idle trunk leading to a connector switch in which a corresponding link is idle at the time. 15 Having determined the idle link and trunk, the incoming and connector switches are operated and the connection is extended through to the called line.

In the event that the operator is extending a connection through one of the incoming switches 201 involving only operators' trunks, the marker is associated with these trunks by means of one of a number of relays 503, 504, etc.

25 For an ordinary trunk group outgoing from one of the regular incoming switches 200, there will be a comparatively large number of trunks requiring a corresponding number of sets of test relays 401. The last 30 four of these sets of test relays only are illustrated in the drawing, comprising the relays 403 to 419, inclusive. In the case, however, of calls extended through the special incoming switches 201, the operators' trunk groups provided for this purpose comprise a comparatively small number, as for example, four trunks. Accordingly, only four sets of test relays 401 in the marker are required. Therefore, the relays 503 and 504 40 above mentioned are provided for connecting the sleeve conductors of these small groups of operators' trunks with the particular four test relays shown in full in the drawing. If the called line occurs in the particular group of connector switches illustrated, then the connecting device 502 will have been 45 operated to associate the marker with the proper switch in this group of connector switches, and accordingly the relay 503 is 50 operated to identify the group of trunks appearing in the vertical row 205 of the incoming switch 201. This particular group of trunks is the one, of course, which leads to the connector switches of the group having 55 access to the called line. Should the called line occur in another connector group, then a relay such as the relay 504 would be operated to associate the marker test relays with the group of trunks appearing in the 60 row 204 which lead to such other connector group. The relay 504 is operated by reason of the fact that some other connecting device similar to the device 502 has been brought 65 into use for associating the marker with the corresponding connector group.

The selective switches illustrated in this drawing may be of the type shown and described in the application of C. L. Goodrum and J. N. Reynolds, Serial No. 486,442, filed July 21, 1921, Patent No. 1,515,735, granted November 18, 1924, and also further described in the application of S. B. Williams, Serial No. 596,179, filed October 23, 1922, Patent No. 1,517,331, granted December 2, 1924.

70 The senders 107, connecting devices 400, markers, and the frame and trunk connecting devices shown in Fig. 5 have been illustrated in abbreviated form, inasmuch as a complete disclosure of these mechanisms is not essential to a complete understanding of the present invention. For a more complete description of the operation of these devices, reference may be had to the application of S. B. Williams, Serial No. 707,795, filed April 21, 1924.

Establishment of an interoffice connection.

First it will be assumed that a connection is to be established over one of the inter-office trunks through incoming and connector switches to the called subscriber's line 307. In any well known manner the operator's attention is called to the fact that a connection needs her assistance. She thereupon assigns the trunk 106 for this purpose and operates an individual assignment key 112, which results in the association of the keyboard 105 with an idle register sender 107 through the agency of the sender selector switch 104. The operator at the distant office upon receiving the assignment of trunk 106, extends the connection over that trunk in the usual manner and also communicates to the operator in the office shown 90 the designation of the called subscriber's line 307. The operator now proceeds to set up the number on her keyboard, whereafter the record thus recorded is transferred 95 through the sender selector 104 to the registers of the sender 107 (not shown). The manner in which these operations take place is described in the application of E. S. Gibson, Serial No. 656,742, filed August 10, 1923, Patent No. 1,559,244, granted October 27, 1925.

100 After the sender has received the record, the sender connector device 400 is operated, associating the sender 107 with the marker shown in the drawing. Thereupon the record is transferred from the registers of the sender to corresponding registers in the marker. Here the record is translated and the proper connecting device 502 is selected 105 for associating the marker with the proper group of connector switches 300. Assuming the connecting device 502 shown is the one to be used, then the relay 505 individual to the particular marker shown is operated. Moreover, the relay 506 which represents 110

the units section 310 in the particular connector switch 300, is also operated. One of the vertical magnets 306 which controls the row of contacts 304 in which appears the 5 called line 307, has been operated in accordance with the translated record received in the marker.

After the marker has been associated with the sender, the proper frame connector 500 10 is selected and operated for associating such marker with the horizontal links of the incoming selector frame 201. The operation of this device consists in energizing the relay 507, which causes the operation of multi- 15 contact relay 510. The circuit for relay 507 extends from battery, through the winding of said relay, conductor 508, front contact of relay 406, back contact of relay 405, to ground at the contact of holding relay 20 402, this latter relay having operated when the marker was taken for use. It will be noted that the relay 406 is operated at this time in a circuit from battery through its winding, through the connector device 400, conductor 420, back contact of relay 111, 25 conductor 421, device 400, conductor 422, to ground at the outer left contact of relay 402.

At the time the connection is extended to 30 the incoming switch 201, the vertical magnet 206 controlling the row of contacts 202 is operated to prepare all of the contacts in this row. The operation of magnet 203 results in the operation of the multi-contact 35 relay 509, which is individual to the particular incoming frame 201. With relays 509 and 510 operated, the test relays of the marker 401 are connected to the corresponding test conductors of the links in switch 40 201.

Since the called line 307 occurs in the group of connector switches 300 to which lead the group of trunks appearing in the vertical row 205 of the switch 201, the corresponding vertical operating magnet 207 is energized to prepare the contacts of this row. The apparatus is now in readiness for making a test of the horizontal links in the switch 201 and the operators' trunks 45 outgoing from the vertical row 205, and also for making a test of a particular horizontal link, such as link 313, having access to the called line 307. For instance, if the line 50 307 appears in a connector switch 300 to which each of the four operators' trunks respectively lead, then a test is made of the particular link 313 shown.

Before the marker can make a test of the links and trunks, however, it is necessary 60 to associate the marker with the trunks of the selected group of operators' trunks. At the time the register sender 107 is associated with the marker and when the frame connector 500 has been operated, the relay 109 of

the sender is operated to indicate that the 65 connection being extended is one involving an operator. The circuit for this relay may be traced from battery, through its winding and normal contact, through the connecting device 400, conductor 425, through contacts 70 of relay 510, contacts of relay 509, thence through contacts of relay 510, conductor 511, to ground at the contact of holding relay 402. Relay 109 operates and locks to ground at the contact of the holding relay 108 which 75 has previously been operated. When relay 109 operated, a circuit was closed for operating the relay 404 in the marker, traceable from battery, through the winding of relay 404, through contacts of the device 400, left 80 contacts of relay 109, conductor 421, and thence through connecting device 400 to ground at the contact of relay 402.

Relay 404 operates the relay 503 which 85 serves to connect the marker test relays to the sleeve conductors of the operators' trunks of the selected group. The circuit for this purpose may be traced from battery, through the winding of relay 503, contact of relay 505, to ground at the contact of relay 404. 90

The testing circuits for the links and trunks will now be traced. The circuit for testing the horizontal link 226 may be traced from battery, through the left winding of test relay 408, contact of relay 407, 95 thence through the connecting device 500 to the sleeve conductor of link 226. Similarly, test circuits may be traced from battery, through the left windings of relays 409, 410 and 411 for the horizontal links 225, 224 and 100 233. The test circuit for testing the operator's trunk 220 may be traced from battery through the right winding of relay 411, contact of relay 407, inner right contact of relay 419, conductor 423, contact of relay 503, 105 to the sleeve conductor of the operator's trunk 220. Likewise, test circuits for the operators' trunks 227, 223 and 222 may be traced through the right windings of relays 408, 409 and 410, respectively. Any of these 110 test relays will operate provided the circuit is closed through either of its windings or if both windings are energized.

Lastly, a test is made to ascertain the condition of the horizontal link 313 of the connector switch before which each of the four operators' trunks appears. The circuit for this purpose may be followed from battery, through the winding of relay 415, conductor 426, connector device 502, conductor 512, to the test conductor 316 on the link 313. If the link is busy, relay 415 operates. 115

It will be assumed that one or more of the horizontal links 226, 225 and 224 and the corresponding trunks 227, 223 and 222 are busy, 120 so that the corresponding test relays 408, 409 and 410 are energized. It will also be assumed that the link 233, the trunk 220 and 125

the link 313 are all idle. Accordingly, the relay 411 and the relay 415 remain deenergized.

As soon as the test has taken place, a circuit is completed from ground, through the contact of relay 402, thence over conductor 427, inner right front contact of relay 404, back contact of relay 415, left front contacts of relays 408, 409 and 410, left back contact

10 of relay 411, winding of relay 419, to battery.

Relay 419 operates and causes the energization of the vertical magnet 305 which controls the row of contacts 301 at the connector switch 300 in which appears the idle trunk 220. This circuit may be traced from battery, through the winding of magnet 305, thence through the contact of relay 503, outer right front contact of relay 419, to ground at the front contact of relay 402.

20 Relay 419 also closes operating circuits for the horizontal magnet 229 of the incoming switch 201 and the horizontal magnet 318 of the connector switch 300. The circuit for magnet 229 may be traced from battery, through the right winding of said magnet, conductor 230, through the frame connector 500, conductor 514, inner left contact of relay 419, to ground at the contact of relay 402. Magnet 229 rotates the horizontal bar (not shown) and extends the trunk 106 over the link 233 to the selected idle trunk 220.

25 The circuit for magnet 318 may be traced from battery, through the right winding of said magnet, conductor 319, through the connector 502, conductor 514, thence to ground as previously traced. The magnet 318 rotates the horizontal bar (not shown) and completes the connection from the trunk 220 over the link 313 to the called subscriber's line 307.

30 It is understood that the called subscriber's line 307 has been previously tested and ascertained to be idle before the connection is extended thereto in the manner described. 45 The manner in which this test is made and also the manner in which the various detailed operations, hereinbefore referred to but not fully shown, take place, may be found in the application to S. B. Williams, Serial No. 707,795, filed April 21, 1924.

35 Before proceeding farther with a description of the manner in which the incoming and final switches are held it may be well to explain the different conditions under which release of these switches is made necessary. Certain of the operators who supervise connections extending through the incoming and final switches have a "no test" key 119 associated with their keyboards. The purpose of this key is to enable the operator to extend a connection to a subscriber's line although such line may actually be engaged at the time. By this expedient the operator may go in on a busy connection and inform the called party that a call is waiting his

attention. In case of a toll or other important long distance call, the called subscriber may desire to discontinue his present conversation and attend to the second call. On the other hand, the called subscriber may 70 wish to disregard the second call, in which case it is necessary for the operator to retire from the connection, releasing the incoming and final switches which she has employed in establishing such second connection. In order to release the connection, the operator restores her release key 113, which was advanced to its operated position automatically when her assignment key 112 was operated. The restoration of the release key 113 removes ground from the sleeve conductor for the purpose of releasing the incoming and final switches. However, since the connection has been extended to a busy line, the tendency of this busy condition is to prevent the 80 release of the incoming and final switches of the second connection. The tying-up of these two switches deprives the operator of their use for an appreciable interval of time, producing a marked inefficiency in the employment of the exchange apparatus.

To obviate this undesirable result, the circuits herein are so arranged that the operator may establish a second connection to a busy line and may thereafter immediately 90 release the connection, restoring the switches employed notwithstanding the fact that the line to which such connection was extended presents a busy condition.

The "no test" key 119 associated with the operator's keyboard 105 when operated results in the energization of a "no test" relay 403 located in the marker in the manner described in the application of E. S. Gibson, Serial No. 656,742, filed August 10, 1923, 100 Patent No. 1,559,244, granted October 27, 1925.

105 It is assumed that the connection which has been previously discussed is one for which the operator did not manipulate her "no test" key 119. Consequently, the "no test" relay 403 remains inert and a circuit is established for the relay 210 individual to the operator's trunk 220 which was taken for use in extending the connection. This 110 circuit may be traced from battery, through the winding of relay 210, contact of relay 503, middle right front contact of relay 419, contact of relay 403, to ground at the contact of relay 402. Relay 210 operates 115 and closes a temporary locking circuit for itself from battery, through its winding and right contacts, conductor 321, contacts of switch 300, to conductor 512. Since the incoming switch 201 is operated at this time, the relay 114 at the operator's position is energized in a circuit from battery, through its winding, sleeve conductor 120, through contacts of switch 201, conductor 238, connector 500, conductor 518, through a contact 120

6
of relay 407, outer left contact of relay 419 to ground. The relay 407 is operated at this time as disclosed in the application of S. B. Williams, Serial No. 707,795, filed April 21, 1924.

Relay 114 operates and locks through the release key 113. Relay 114 also applies ground potential to the conductor 120.

Relay 208 is now operated in a circuit 10 from battery, through its normal contact and right winding, over the holding conductor of trunk 220, through the switch 201, to the grounded conductor 120 of trunk 196. Relay 208 operates and locks in a circuit 15 from battery, through the winding of relay 209, outer left front contact of relay 210, inner right contact and right winding of relay 208, to ground as above traced. Slow-release relay 209 operates in this circuit. 20 The holding circuit for relay 210 is now completed from battery, through its winding and inner right contact, to ground at the outer right contact of relay 209.

As soon as the marker is released and 25 the vertical operating magnets 206 and 207 are deenergized, the connection through switch 201 is maintained by the magnet 229 which is held in a circuit from battery, through both its windings, contacts of 30 switch 201, to the grounded sleeve conductor 120. Similarly, the connector switch 300 is maintained operated by the continued energization of magnet 318 in a circuit from battery, through both its windings, contact 35 of switch 300, conductor 321, outer right front contact of relay 210, to ground at the outer right contact of relay 209.

The relay 209 completes a circuit for applying ground potential to the sleeve conductor of the called subscriber's line 307 to render the same busy, and this circuit may 40 be traced from ground, through the outer right contact of relay 209, conductor 232, through contacts of the switch 300, to the 45 sleeve conductor of the subscriber's line 307.

When it is desired to release the connection, the operator restores her release key 113, thereby removing ground potential from the holding conductor 120. This results in the deenergization of relay 209 and the consequent release of the incoming switch 201. Moreover, the circuit of relays 208 and 209 is opened, resulting in the de-energization of relay 208. Relay 209, however, being slow requires an interval in which to retract its armatures. If the called subscriber 307 has replaced his receiver on the switchhook, the relay 209 releases after a measured interval, and in so doing removes ground from the conductor 232, causing the release of relay 210 and of the magnet 318, thereby disconnecting the trunk 220 from the called subscriber's line and restoring the connector switch 300.

65 However, if the called subscriber main-

tains his receiver off the switchhook after the operator has released, the relay 209 finds a new energizing circuit, which may be traced as follows: Battery, through the winding and inner right contact of relay 209, right back contact of relay 208, thence over the ring side of the connection, including the loop of the called line 307, and returning over the tip side of the connection through the inner left contact of relay 209, to ground at the inner left back contact of relay 208. Relay 209 therefore remains energized and maintains the busy condition on the holding conductor of trunk 220, preventing the release of the connector switch 300.

Immediately that relay 208 releases, a circuit is closed from battery, through the winding and contact of the pick-up relay 211, outer left contact of relay 209, outer left contact of relay 208, to the lower contact of interrupter 212. As soon thereafter as the interrupter 212 closes its contact, relay 211 operates and locks to the grounded conductor 232. Upon the next closure of 90 the upper contact of the interrupter 212, a circuit is closed from battery, through the left winding of relay 208, left contact of relay 211, to ground at the contact of interrupter 212. Relay 208 operates and opens 95 the circuit of relay 209, which releases and causes the release of the connector switch 300.

Thus, if the operator fails to manipulate 100 her "no test" key and the called subscriber maintains his receiver off the switchhook, the connector switch 300 remains in its operated condition until the interrupter 212 measures off this predetermined interval of time. By 105 holding the connector switch in its operated condition after the calling subscriber has replaced his receiver, a ground potential is maintained on the sleeve of the called line. This prevents the called line from falsely initiating the operation of a line switch due 110 to the fact that the called subscriber's receiver is still off the switchhook.

It will next be assumed that the operator is handling a toll or other important connection which she desires to extend to the 115 called subscriber's line regardless of whether his line may be busy or not. Accordingly, to anticipate the busy condition of the called line, she manipulates her "no test" key 119, whereby the "no test" relay 403 in the 120 marker is subsequently operated. When the connection is later set up through the incoming and final switches, the relay 211 fails to operate as previously described, 125 since the circuit for energizing the same is now opened at the contact of relay 403.

When the switch 201 operates, relay 208 becomes energized in a circuit traceable from battery, through the contact and right winding of said relay, contacts of the switch 201, 130

to the grounded conductor 120. Relay 208 operates and locks in a circuit from battery, through the left back contact of relay 210, inner right contact and right winding of relay 208, and thence to ground over the sleeve conductor 120 of trunk 105. Since the relay 210 remains deenergized, relay 209 is not furnished with an operating circuit. The connector switch 300 is now held by means of a circuit from battery, through the windings of the horizontal magnet 318, contacts of the switch 316, conductor 321, left inner back contact of relay 210, to ground at the inner left front contact of relay 208. The relay 208 also applies ground potential to the sleeve conductor of the called subscriber's line 307, in order to render the same busy in case such line is idle. The circuit for this purpose may be traced from ground, through the outer right contact of relay 208, outer right back contact of relay 210, conductor 232, contacts of the switch 300, to the sleeve conductor of the line 307. It will be noted in this case that the relay 209 is not connected across the tip and ring conductors of the called subscriber's line. Therefore, it does not matter whether the called line 307 is busy or not. The operator may release the connection which she has extended thereto immediately without waiting for the time measuring device 212.

When the operator desires to release, she throws the release key 113, removing ground potential from the conductor 120. This results in the release of switch 201 and also in the release of the relay 208. Relay 208 removes ground potential from conductor 321, whereby the connector switch 300 is released immediately.

Consideration will next be given to the establishment of a local connection through one of the regular incoming selector switches 200. If the subscriber of the line 100 initiates a call, his line is extended through line switch 101 to an idle trunk 102 leading to the district selector switch 103. The trunk 102 is also associated with an idle sender 107 through the sender selector switch 104. After a marker has been associated with the sender, the district selector switch 103 is operated and the connection is extended over an idle trunk 115 appearing in the vertical row of contacts 213 in the incoming selector switch 200. The frame and trunk connectors 500 and 501 and the connecting device 502 are operated for associating the marker with the proper incoming and final switches and also with the proper group of trunks interconnecting the same.

It may be assumed that the trunks appearing in the vertical row 216 constitute the group leading to the group of connector switches 300 having access to the called line 307. Only two of these trunks have been

shown, but it will be understood that as many will be provided as are necessary.

The marker performs a test of the horizontal links in the switch 200 and of the trunks 219, 220, etc., and also of the horizontal links in the connector switch 300, in substantially the same manner as that previously discussed in connection with the operation of the switch 201. In this instance, however, the test circuits for the trunks 219, 220, etc., extend through contacts of the trunk connector 501. None of the relays 503 or 504 is operated, due to the fact that the relay 404 in the marker remains deenergized. Relay 404 is not operated owing to the fact that the operator's relay 109 in the sender has not been operated on this type of call. If the test reveals that the link 235, trunk 220 and link 313 are idle simultaneously, relay 419 is operated in a circuit from ground over conductor 427, through the back contact of relay 404, left front contacts of relays 408, 409 and 410, left back contact of relay 411, winding of relay 419, to battery. Relay 419 operates and in the manner hereinbefore described causes the operation of the horizontal magnets 236 and 318 to extend the connection through the switches 200 and 300 to the called subscriber's line 307.

In this case, the relay 403 being deenergized, the relay 210 operates, causing the operation of relay 209 and thereby placing the release of the connector switch 300 and the trunk 220 under the control of the called subscriber's line and also under the control of the time measuring device 212.

The release of the connection takes place in substantially the same manner as previously explained herein.

A system of the character hereinbefore described may also be employed for verifying numbers of calling subscribers' lines.

Certain other features disclosed in this application are being claimed in a copending application of S. B. Williams, Serial No. 726,268, filed July 16, 1924.

What is claimed is:

1. In a telephone system, a line, a selective switch, an operator's position, means under the control of the operator for extending a connection to said switch, means for operating the switch to further extend the connection to said line, release means at the operator's position for releasing the connection to said switch, means controlled by the line for holding said switch operated after the operator has released said connection, and means for placing the release of said switch directly under the control of said release means independently of said line.

2. In a telephone system, a line, a selective switch, an operator's position, means under the control of the operator for extending a connection to said switch, means for operating the switch to further extend the

connection to said line, release means at the operator's position for releasing the connection to said switch, means effective if the line remains busy for holding said switch after the operator has released the connection thereto, and means for enabling said release means to cause the release of said switch simultaneously with the release of the connection regardless of the condition of the line.

3. In a telephone system, a telephone line, an automatic switch, an operator's position, means under the control of the operator for extending a connection to said automatic switch, means under the control of the operator for operating said switch to further extend the connection to said line, a release key at the operator's position for releasing the connection to said switch, means effective if the line remains busy for holding said switch after the operator has released the connection thereto, means for releasing said switch at the end of a definite interval after the connection has been released independent of said line, and means for placing the release of said switch directly under the control of said key independently of said line.

4. In a telephone system, a subscriber's line, a trunk, means for extending a connection to said trunk, automatic means for extending said trunk to the subscriber's line, release means for releasing the connection to said trunk, means dependent on the continued busy condition of said line for holding said trunk in connection therewith fol-

lowing the release of said connection, and means for rendering said release means effective to cause the release of said trunk simultaneously with the release of said connection regardless of the condition of the subscriber's line.

5. In a telephone system, a line, a selective switch, an operator's position, means under the control of the operator for building up a connection to said switch, a controlling mechanism for governing the operation of said switch to further extend the connection to said line, release means at the operator's position for releasing the connection to said switch, means controlled by the line for holding said switch operated after the operator has released said connection, and means rendered effective by said mechanism for placing the release of said switch directly under the control of said release means.

6. In a telephone system, a line, means for extending a connection in the direction of said line, a selective switch having a number of links for further extending said connection to said line, means for operating said switch, release means for releasing the connection extended to said switch, means controlled by the line for holding said switch operated after the operator has released said connection, and means for placing the release of said switch directly under the control of said release means independently of the line.

In witness whereof, I hereunto subscribe my name this 14th day of July A. D., 1924.

EARL S. GIBSON.
